CLAIM

The ornamental design for a combined can shaped gift card holder with can cooler, as shown and described.

DESCRIPTION

FIG. 1 is a perspective view of the combined can shaped gift card holder with can cooler of the present invention, in a closed position.

FIG. 2 is a front view thereof.

FIG. 3 is a rear view thereof.

FIG. 4 is a top down view thereof.

FIG. 5 is a bottom up view thereof.

FIG. 6 is a right side view thereof, the left side view being a mirror image thereof.

FIG. 7 is a perspective view thereof, in an open position.

FIG. 8 is a front view of FIG. 7; and,

FIG. 9 is a right side view of FIG. 7, the left side view of FIG. 7 being a mirror image thereof.

The broken lines showing of a gift card with a dollar sign, depict environmental structure and forms no part of the claimed design. The remaining broken lines illustrate portions of the combined can shaped gift card holder with can cooler that form no part of the claim. The surface between the horizontal lines, on the can portion in FIGS. 1, 2, 7 and 8, forms part of the claim.
